US00D939302S

(12) **United States Design Patent** (10) Patent No.: **US D939,302 S**
(45) Date of Patent: **** Dec. 28, 2021**

(54) **CORKSCREW**

(71) Applicant: **BABYLISS FACO SRL**, Wandre (BE)

(72) Inventor: **Aubry Ernote**, Theux (BE)

(73) Assignee: **BABYLISS FACO SRL**, Wandre (BE)

(**) Term: **15 Years**

(21) Appl. No.: **35/510,000**

(22) Filed: **Jul. 14, 2020**

(80) **Hague Agreement Data**

Int. Filing Date: **Jul. 14, 2020**

Int. Reg. No.: **DM/209544**

Int. Reg. Date: **Jul. 14, 2020**

Int. Reg. Pub. Date: **Aug. 7, 2020**

(30) **Foreign Application Priority Data**

Jan. 16, 2020 (EM) 007520945-0001

(51) LOC (13) Cl. **07-06**

(52) U.S. Cl.

USPC **D8/36**

(58) **Field of Classification Search**

USPC D8/33, 36, 42, 43

CPC B67B 7/0405

See application file for complete search history.
